WILLIAM W. BOYINGTON, OF CHICAGO, ILLINOIS.

Letters Patent No. 78,046, dated May 19, 1868.

IMPROVED PAVEMENT.

The Schedule referred to in these Letters Patent and making part of the same.

TO ALL WHOM IT MAY CONCERN:

Be it known that I, WILLIAM W. BOYINGTON, of Chicago, in the county of Cook, and State of Illinois, have invented a new and useful Improvement in Pavements; and I do hereby declare the following to be a full, clear, and exact description of the same, reference being had to the accompanying drawings, in which—

Figure 1 is an isometrical view of my pavement partially completed.

Figure 2 is a vertical section of the same in the direction of the street, the pavement being exhibited as completed.

My invention relates to that class of pavements known as "wood pavements," but consisting of a combination of wood and concrete, and my invention, as secured in this patent, consists in an improved manner of arranging and securing the wood blocks upon the foundation, so as to secure the following-named advantages:

First, prevention of lateral movement upon the foundation.

Second, prevention of the working out of any of the wooden parts.

Third, a depth of concrete, nearly or quite equal to the height of the paving-blocks.

Fourth, a sufficient foundation, with a less expenditure of material.

Pavements of the kind above mentioned have usually been constructed as follows: First, a foundation of boards has been laid upon the graded roadway. This foundation consists of two thicknesses of boards laid transverse to each other and nailed together. Upon said foundation are arranged rows of wooden blocks, made by cutting four-inch planks, transverse to the grain, into lengths of about eight inches. These rows extend from side to side of the street, and have intervals of about one and one-fourth inch between the rows. To insure uniformity of said intervals, as well as to facilitate the operation of laying the pavement, strips of board are used, said strips being in thickness equal to the width of the interval, and in width about four inches. After placing one row of blocks, one of said strips is placed with its side against the side of said row, and its lower edge resting upon the foundation. In this position said strip is nailed fast to the block, and perhaps to the foundation also. Another row of blocks is then arranged against said strip and nailed, and then another strip, and so on until the roadway is covered. The pavement now presents a surface of wood, crossed by narrow grooves of four inches in depth and one and one-fourth inch in width. These grooves are filled with concrete, of gravel or other similar material, mixed with melted pitch, &c.

Pavements so constructed present several features marking a deficiency in excellence.

First, the strips and blocks become detached from the foundation, and, after a time, are found to have moved thereon, so that the rows, which were originally straight, become curved.

Second, the strips themselves become detached, and work to the surface, forcing the concrete out of the grooves, and leaving the blocks loose at the bottom.

Third, if the strips remain in place there will be only a depth of four inches subject to wear before the concrete will have disappeared, and it will be necessary to lay the pavement anew.

All of the above-mentioned defects are remedied by the method of constructing a pavement which I have invented, and which I will now describe.

As in other styles of pavement, the roadway is first to be graded and the surface properly prepared to receive the foundation-boards, A A, which, though not always necessary, I prefer to use. When laying said foundation-boards they are arranged lengthwise of the street, single thick, and transverse boards D are placed beneath their butting ends, for the purpose of properly breaking joints, to prevent the sinking of said ends under heavy travel. The ends of the boards A are arranged properly upon the cross-board D, and securely nailed fast thereto.

I now arrange a row of blocks, C C, which are made as above described, by cutting plank of, say four inches' thickness, or thereabouts, into lengths of from six to eight inches. These blocks C are placed edge to edge, and grain-ends upward, as shown in fig. 1, in a row extending from side to side of the street, or arranged diagonally thereto in patterns, or otherwise, as may be desired, and next to said row of blocks I firmly nail to

the foundation a plate-board, B, say about six or six and a half inches in width, so that the blocks C are in contact with the edge of said strip.

Previous to placing the plate B in position upon the foundation, I securely nail to it, along its centre, a row of blocks, C' C'. When the plate B has been secured in position, then another row of blocks C C is placed against its other edge, and so on.

In practice, the plates B, with rows of blocks, C' C', attached, may be laid and secured before the blocks C C are arranged in place, the proper spaces for said rows of blocks being adjusted by using gauge-strips, which may be removed when the plates are secured.

The mechanical details to be adopted are, however, unimportant, and the order of operation may be raised to suit the requirements of the case.

The blocks C' C' are cut shorter than the blocks C, by as much as the thickness of the plate B, so that when in position the tops of the rows C C C' C' will be on the same plane. I repeat the above-described operation until the roadway has been covered, each alternate row being composed of long blocks, standing directly upon the foundation, and the intermediate rows, composed of short blocks, standing upon the plates B, and intervals of about one inch in width between the rows of long and short blocks. These intervals I fill with concrete, composed of broken stone, gravel, sand, or other suitable material, mixed with hot pitch, asphaltum, or other proper cementing substance.

It will be perceived that a pavement, so constructed, cannot become detached from and move upon the foundation, because each alternate row C is, as it were, embedded in said foundation; that is to say, said rows are confined at their lower ends by the transverse plates B, which at once serve to equalize the distance between the rows, facilitate the operation of laying the pavement, and retain the whole firmly in place. No strips can be displaced, and rise to the surface, so as to displace the concrete, and make the pavement loose at the bottom; nor can the pavement creep upon the foundation, so as to lengthen the rows, and, as the concrete extends from the surface to the bottom of the shorter blocks C', a distance of six or seven inches, my pavement may be worn down to a much greater degree, before becoming disabled, than any other now in use.

It will also be perceived that there is an economy of material, for whereas, in the common road-pavement hereinbefore described, there is a thickness of solid wood extending from the surface of the ground upward about six inches, and above that a thickness of about four inches of combined wood and concrete, in my pavement there is only a thickness of two inches of wood, and a depth of wood and concrete of about seven inches, subject to wear.

It would, of course, be desirable, where practicable, to saturate all of the wood used in this pavement with some preservative substance or preparation, to render it impervious to water, and to prevent exhalations from it in warm weather.

If it is desired, the wooden portion of my pavement may be constructed in sections, to be arranged upon the road-bed when completed, and before the concrete is applied; to do so, requiring nothing more than the skill of ordinary mechanics.

Having described my invention, what I claim as new, is—

A foundation for a wood and concrete-pavement, formed with a layer of boards, A, lengthwise with the street, and a layer of plates, B, transverse, and nailed fast thereto, said plates being of equal widths, and with spaces between equal to the thickness of the blocks composing the wooden portion of said pavement, substantially as described.

The combination of the foundation A B, constructed as described, with the blocks C and C', and concrete-filling, in the manner and for the purpose herein set forth.

WM. W. BOYINGTON.
